UNITED STATES PATENT OFFICE.

REDMOND J. McGRATH, OF CHICAGO, ILLINOIS, ASSIGNOR OF ONE-HALF TO DANIEL W. MURPHY, OF CHICAGO, ILLINOIS.

COMBINATION SHAFT-HANGER AND BELT-TIGHTENER.

960,571.

Specification of Letters Patent.

Patented June 7, 1910.

Application filed September 14, 1908. Serial No. 452,937.

To all whom it may concern:

Be it known that I, REDMOND J. McGRATH, a citizen of the United States, residing at Chicago, county of Cook, and 5 State of Illinois, have invented certain new and useful Improvements in Combination Shaft-Hangers and Belt-Tighteners, of which the following is a specification.

My invention relates to improvements in 10 combination shaft-hangers and belt-tighteners, the object being to provide, in a hanger depending from a ceiling, means for carrying a counter-shaft and a plurality of idler pulleys, one of which is adjustable.

15 A further object of my invention is to arrange idler pulleys and the drive-belt from a main drive-pulley to the counter-shaft pulley in such a manner that said counter-shaft and said drive-pulley may rotate in opposite directions without crossing the drive-belt.

Other objects will appear hereinafter.

With these objects in view, my invention 20 consists in a shaft-hanger suitably attached to and depending from a ceiling, bearings in said hanger for a counter-shaft and an idler pulley, and a horizontally disposed slot in said hanger in which a shaft carrying a second idler pulley is slidably mounted.

25 My invention further consists in certain details of construction and arrangement of parts all as will be hereinafter fully described and particularly pointed out in the claim.

30 My invention will be more readily understood by reference to the accompanying drawings forming a part of this specification, and in which—

Figure 1 is a side elevation of my improved shaft-hanger and belt-tightener in 35 its preferred form, and Fig. 2 is a transverse section taken substantially on the line $x-x$ of Fig. 1.

Referring now to the drawings, 1 indicates the body of the shaft-hanger, and 2 the ceiling to which it is attached. Slots 3 are provided in order that the hanger may be 40 adjusted to the proper position before the screws 4 are tightened. The counter-shaft 5 is journaled in a bearing in the hanger which is provided with the cap 6, and the pulley 7 is rigidly secured to said counter-shaft. The drive-pulley 8 is secured to the 45 drive-shaft 9 and is adapted to rotate in the direction indicated. An idler pulley 10

is rotatably mounted on the shaft 11 which is secured in the frame 1, and the idler pulley 12 is rotatably mounted on the shaft 13 which is adjustably mounted in the slots 14. The pulley 12 is provided with reduced 50 extensions 15 to maintain the central position of the main body portion of said pulley. Rectangular plates 16 are provided with perforations and are loosely mounted on the shaft 13. The plates 16 are arranged on 55 either side of the slotted portions 14, the inner plates being adapted to abut the extensions 15 in the pulley 12, and the outer plates to be held in position by means of the nuts 17. Blocks 18 are slidably mounted in the slots 14 and are perforated to receive the shaft 13. An adjusting screw 19 is provided on either side of the hanger and the latter is tapped to receive the same. The blocks 18 are adapted to slide along the 60 slots 14 and to tighten the belt 20 when the screw 19 is tightened against the tension of said belt. A lock-nut 21 is provided on the screw 19 to secure the adjustment of the same.

While I have shown what I deem to be the preferable form of my improved shaft-hanger and belt-tightener, I do not wish to be limited thereto as there might be many changes made in the details of construction 65 and arrangement of parts without departing from the spirit of my invention.

Having described my invention what I 70 claim as new and desire to secure by Letters Patent, is:

In a device of the class described, a pair 75 of similar hanger brackets, each of said brackets comprising a base having slots to receive bolts for securing the device to the ceiling and a depending portion, said depending portion being provided with a horizontally disposed slot adjacent its upper end and parallel with the slots in said base portion, a block slidably mounted in each of said slots, a screw threaded through the 80 end of the bracket and impinging against its respective block, a pulley shaft having its ends mounted in said blocks, a pulley on said shaft having reduced ends, bearings formed on said brackets adjacent said 85 screws and in a plane below the same, a counter-shaft mounted in said bearings and a pulley on said shaft, and an idler pulley and a shaft for the same having bearings in the lower end of said brackets below the 90

plane of said counter-shaft, in combination with a driven pulley and a belt passing about said driven pulley, the first said pulley, said counter-shaft pulley and said 5 idler pulley successively, substantially as described.

In testimony whereof I have signed my

name to this specification in the presence of two subscribing witnesses.

REDMOND J. McGRATH.
